APPARATUS FOR MAKING MULTIPLE ARTISTIC DESIGNS

Louis Jackson, New York, N. Y.

Application August 1, 1952, Serial No. 302,276

6 Claims. (Cl. 41—1)

1

This invention relates to an apparatus for making multiple artistic designs.

It is an object of the present invention to provide an apparatus adapted to make a multiple number of artistic designs of the same shape and color on blotting paper squares and wherein coloring dyes and liquids can be fed to a stack of these blotting and highly absorbent squares.

It is another object of the invention to provide an apparatus for making a multiple number of similar artistic designs on absorbing paper squares wherein the liquid delivering felts are suspended from pans on a carriage adjustable over stationary drain pans or trays to which the felts extend and wherein these carriages are held against the action of springs toward the stack of absorbent squares and a cable cord is extended about the carriages and holds them against the stack of absorbent squares.

It is another object of the invention to provide an apparatus for making a multiple number of artistic designs from absorbent paper sheets wherein the designs can be observed upon the bottom sheet by mirror means as well as the top sheet is observed.

Other objects of the invention are to provide an apparatus for making a multiple number of absorbent sheet designs, which is of simple construction; inexpensive to manufacture, has a minimum number of parts, easy to operate, compact, convenient to use and efficient in operation.

For other objects and for a better understanding of the invention, reference may be had to the following detailed description taken in connection with the accompanying drawing, in which:

Figure 1 is a perspective view of the apparatus construction according to the present invention.

Fig. 2 is an enlarged vertical sectional view taken on line 2—2 of Fig. 1.

Fig. 3 is a fragmentary sectional view similar to Fig. 2 but with the vertically-extending felts in engagement with a stack of absorbent sheets to deliver the liquid to the edges thereof.

Fig. 4 is a fragmentary elevational view showing the manner in which one of the cable pulleys is attached to the vertically-extending carriage slide, the view being taken on line 4—4 of Fig. 2.

Fig. 5 is a horizontal view taken on line 5—5 of Fig. 2.

Fig. 6 is a vertical sectional view taken on line 6—6 of Fig. 2.

Fig. 7 is a fragmentary perspective view looking upon the felt delivery members and showing the ends thereof extended into the liquid delivery and receiving trays, and

2

Fig. 8 is a stack of completed absorbent sheets bearing the artistic designs.

Referring now to the figures, 10 represents a base having a bottom portion 11 and an elevated top and supporting portion 12. The top portion is held in vertically-spaced relationship from the bottom portion 11 by corner post portions 13.

Resting on the bottom portion is a large mirror 14, the purpose of which to be later described. 10 The top portion is square and intermediate the ends of each side thereof are upstanding portions 15 which serve as supports for slide rods 16. Each slide rod is connected to a carriage 17 that has a tray supporting portion 18. This tray supporting portion has two partitions 19 providing three spaces receiving respectively elongated trays 21. These trays are adapted to contain the colored liquid for dye which is used for coloring the absorbent or blotting paper squares or sheets 22.

20 The top portion 12 has a central square opening 23 and raised tray supporting portions 24 having partitions 25 forming spaces into which elongated bottom trays 26 are fitted. The bottom trays 26 are longer than the upper trays 21 and the inner ends thereof extend inwardly of the front of the carriage 17. The carriage 17 has bottom wheel devices 27 which ride over the bottom tray supporting portions 24 on the top portion 12 of the base 10.

25 The carriage 17 provides a front face 28 downwardly over which extend felt strips 29. Each end of the felt strip 29 is bifurcated to provide portions adapted to be extended into the respective trays 21 and 26. There are three felt strips 30 29 on the front face of each carriage. The front face has pairs of grooves 31 disposed between the felt strips to prevent the flow of liquid from one felt to the other and in such a manner as to discolor the liquid of any one of the felt strips.

35 In the end of the space provided for the trays 21 is a wire mesh 32 which projects upwardly above the upper edge of the trays 21 to engage the bifurcated portions of the felt strips 29 and to hold them against outward and downward displacement from the trays 21. The upward bifurcated portions are indicated at 29' and it will be seen that these portions extend over the upper edge of the tray supporting portion 18 and into the trays 21. The wire mesh 32 is held vertically in the spaces for the trays and projects upwardly a sufficient distance from the upper edge of the trays to engage the portions 29' as indicated at 32', Figs. 2 and 3. The trays 21 are filled with the different colored liquids according to the pattern desired upon the absorbent sheets 22. This liquid

in the trays 21 is indicated at 34 and it travels upwardly through the bifurcated portions 29' of the felt strips and downwardly through the main body of the felt strips 29 to bifurcated portions 29" on the lower ends of the strips 28, which respectively extend into the bottom trays 26. The liquid will accordingly flow downwardly from the trays 21 to the trays 26 as illustrated in Figure 3 so that the felt strip is kept saturated with the colored liquid or dye.

The multiple or stacked absorbent sheets 22 are supported on a glass 35 which rests on the upper edges of the lower tray supporting portions 24 over the square opening 23.

The slide rod 16 is bent at its inner end and secured to the carriage 17 by a screw 36. The slide rod is bent at its outer end as indicated at 37. A tension spring 38 extends between the bent end 37 of the slide rod and a post device 39 carried on the upstanding projection 15. This post device comprises a plate 41 that has a bent upper end portion 42 which extends over slide rod 16. This plate 41 is pivotally connected to the side of the projection 15 by a screw bolt 43 that is held in place on the projection by a nut 44. An enlarged hole 45 is provided in the plate above the screw bolt 43, to receive a bolt 46 that is held in place in the projection 15 by a winged clamp nut 47. By having the large hole 45, the plate 41 can be shifted fore and aft to have its bent end portion engage the flat slide rod 16 in such a manner as to hold the slide rod clamped in its adjusted position on the upper end of the projection 15. Tabs 48 are provided on the upper end of the projection 15 to hold the slide rod 16 against lateral displacement on the upper end of the projection 15. A pulley wheel 49 is journaled on upstanding post 50 on the bent end 42 of the device.

With the absorbent paper squares or sheets 22 in place on the glass support 35, the carriages will be adjusted and urged toward the edges of the absorbent squares by their respective tension springs 38 acting on the guide rods 16. The different colored liquids are poured into the top trays 21 and this liquid will flow outwardly and downwardly along the felt strips for delivery to the edges of the absorbent sheets. The mass of absorbent sheets will absorb the liquids equally so that a definite and similar pattern will be made on each of the sheets. One pattern is indicated at 51 on the sheet 22 as shown in Fig. 8. In order to observe the bottommost sheet of the stack through the glass plate 35, to make sure that the bottom sheet has the same figure as the upper sheet and has been fully saturated with the liquids, openings 52 are provided in the top portion 12 at each corner thereof through which the operator can look upon the mirror 14 in the manner illustrated in Fig. 2 to view the bottommost absorbent sheet.

The carriages 17 are accordingly spring urged inwardly by the tension springs 38 upon loosening the clamp nuts 47 of the post device 39 and extending wire 53 over all of the pulleys 49 and fixing it to a bracket post 54 on the top portion 12 of the base, all of the carriages will be retained together so as to prevent the need for individually turning each clamp nut 47 when it is desired to release the carriages. It will only be necessary to release the wire 53 from the bracket post 54 to obtain this result.

It should now be apparent that with this device a multiple number of absorbent squares or sheets can be provided with colored patterns with one

set up of the apparatus. The parts of the apparatus will be preferably made of materials such as plastic which can be easily cleaned and kept from becoming stained by the dyes or liquids.

5 These parts may be molded or fabricated from stock pieces.

It will be seen that by the provision of a mirror the bottommost sheet can be observed at all times. Also it will be seen that the carriages can be readily adjusted and that each carriage is individually spring urged toward the stack of sheets and that by the use of the wire 53 individual clamping of the carriers is unnecessary.

While various changes may be made in the detailed construction it shall be understood that such changes shall be within the spirit and scope of the present invention as defined by the appended claims.

What is claimed is:

1. An apparatus for making multiple artistic designs comprising a base having a bottom portion and a supporting portion upwardly spaced therefrom, said supporting portion having a central opening, a transparent plate adapted to fit over the central opening and to support a stack of absorbent sheets, a liquid delivery carriage adjustably mounted on the supporting portion and having an elevated tray portion, an absorbent felt liquid delivery strip extending from the elevated tray portion and downwardly over the front of the carriage for engagement with the side edges of the absorbent sheets to deliver liquid thereto, a mirror mounted on the bottom portion of the base under the transparent supporting plate for the absorbent sheets, said supporting portion having an opening therein to permit the operator to observe upon the mirror the progress of absorption of liquid of the bottommost absorbent sheet of the absorbent sheet stack.

2. An apparatus for making multiple artistic designs comprising a base having opposite sides, upstanding projections on the respective opposite sides of the base, liquid delivering carriages disposed on the respective opposite sides of the base, means for respectively adjustably connecting said carriages to said upstanding projections of the base, said carriages comprising respectively an elevated tray portion and absorbent felt liquid delivering strips extending from the tray portions and downwardly over the forward faces of the carriages and adapted to engage the edges of a stack of absorbent sheets to deliver liquid thereto, and clamp devices on the respective upstanding projections and engageable with the respective carriages to retain the carriages in their adjusted positions and individually adjustable to fix the respective carriages in their adjusted positions.

3. An apparatus for making multiple artistic designs as defined in claim 2, said respective clamp devices on the projections having portions adapted to receive a wire, wire means extending about the base and engageable with the respective wire receiving portions of the clamp device and an upstanding bracket on said base for the fixing of the opposite ends of the wire thereto whereby said clamping devices can be held in unison by said wire.

4. An apparatus for making multiple artistic designs comprising a base having opposite sides, upstanding projections on the respective opposite sides of the base, liquid delivering carriages disposed on the respective opposite sides of the base, means for respectively adjustably connecting said carriages to said upstanding

projections of the base, said carriages comprising respectively an elevated tray portion and absorbent felt liquid delivering strips extending from the tray portions and downwardly over the forward faces of the carriages and adapted to engage the edges of a stack of absorbent sheets to deliver liquid thereto, said means for adjustably connecting each of said carriages to the upstanding projection including a flat slide rod extending over the upper edge of the upstanding projection and spring biasing means extending between the rod and the upstanding projection for normally urging said carriages toward the center of the base and against the edges of absorbent sheets.

5. An apparatus for making multiple artistic designs as defined in claim 2, said means for adjustably connecting said carriage to the upstanding projection including a slide rod, said clamp device being engageable with the slide rod to retain the slide rod and thereby the carriage in the adjusted position, said clamp device having an upstanding post, and a tension spring connected between the slide rod and the upstanding post for normally urging the carriage toward the stack of absorbent sheets upon release of the clamp device.

6. An apparatus for making multiple artistic

designs comprising a base having opposite sides, liquid delivering tray carriages disposed on the opposite sides of the base and adjustable toward the center thereof for engagement with the side edges of a stack of absorbent sheets to deliver coloring liquid thereto, said carriages having a front portion, an elevated tray portion extending rearwardly from the front face portion, absorbent felt delivery strips extending out of the tray portion and downwardly over the front face portion for engagement with the side edges of the absorbent sheets, individual liquid trays adapted to be disposed in the elevated tray portion and receiving said liquid delivery strips, and wire mesh elements disposed between the front of the elevated tray portion and the forward end of the individual tray and projecting upwardly in an edgewise manner to engage the liquid delivery strips and to retain the same against forward displacement from the individual trays.
